UNITED STATES PATENT OFFICE

CHARLES O. KNUUTI, OF BERWYN, ILLINOIS, ASSIGNOR TO WESTERN ELECTRIC COMPANY, INCORPORATED, OF NEW YORK, N. Y., A CORPORATION OF NEW YORK

PERCUSSIVE APPARATUS

Application filed December 26, 1929. Serial No. 416,465.

This invention relates to percussive apparatus, and more particularly to motive fluid actuated percussive apparatus.

This invention has been found particularly useful in upsetting rivets by a percussive action of a tool thereagainst, particularly rivets having long slender shanks wherein heretofore it has been somewhat difficult to rivet them successfully without bending or deforming the shanks.

The primary object of this invention is the provision of an improved percussive apparatus wherein the percussive element is simultaneously reciprocated and rotated to produce a combined spinning and impacting action upon a work piece.

In accordance with one embodiment of this invention as applied to a bench type riveter, a motive fluid is directed to a piston for causing reciprocation of a riveting tool, a portion of the fluid being diverted into contact with a turbine rotor surrounding and being connected to the tool by a sliding connection. Under these conditions the tool is caused to rotate with the rotor during reciprocation of the tool so that a simultaneous reciprocation and rotation of the tool is effected continually when it is in an operative position.

Other objects and advantages of this invention will more fully appear from the following detailed description, taken in connection with the accompanying drawing, wherein

Fig. 1 is a side view of one embodiment of this invention shown partly in section;

Fig. 2 is an enlarged horizontal section taken on the line 2—2 of Fig. 1;

Fig. 3 is a fragmentary vertical irregular section through the motive fluid actuated elements taken on the line 3—3 of Fig. 2;

Fig. 4 is an enlarged detail view of a portion of Fig. 3;

Fig. 5 is a detail horizontal section taken on the line 5—5 of Fig. 4;

Fig. 6 is an enlarged detail vertical section of the end of a riveting tool taken on the line 6—6 of Fig. 3, and

Fig. 7 is a plan section taken on the line 7—7 of Fig. 6.

Referring now to the drawing in detail in which like reference numerals designate similar parts throughout the several views, and particularly to Fig. 1 which illustrates the features of this invention applied to a bench type riveter, 10 represents a supporting standard secured to a bench surface 12. The standard 10 at its upper end is provided with an offset cylindrical collar portion 13 within the bore of which is reciprocably mounted a sleeve 14, the periphery of which at its right side has formed therein a series of rack teeth 17. Fixed to a shouldered shaft 18 journaled in the standard 10 is a gear 19 (dotted lines Fig. 1) which meshes with the rack teeth 17 on the sleeve 14, the gear being secured to the shaft within a suitable pocket (not shown) formed in the standard. The shaft 18 at its forward end is formed with an enlargement 20 within a bore of which is fitted a rod 21 extending at right angles to the longitudinal axis of the shaft, the rod being longitudinally adjustable in the bore and thereafter secured in position by a screw 24. At its rear end the shaft 18 is provided with suitable retaining means, such as a nut (not shown), threaded thereonto for preventing a longitudinal movement of the shaft in the bore of the standard.

To one end of the rod 21 is pivotally secured one end of a link 26, the opposite end of the link being connected to a suitable treadle mechanism (not shown), the treadle and the operatively connected parts being returned to their normal position as shown in the drawing by a spring or weight (not shown). The arrangement is such that upon a depression of the treadle the link 26 will be moved upwardly and as a result the gear 19 will be rotated counter-clockwise and by means of the teeth thereof meshing with the rack teeth 17 on the sleeve 14, the latter will be moved downwardly in the bore of the cylindrical collar portion 13 of the standard 10 and upon a release of the treadle the spring or weight acts to return the parts to their normal position.

Fitting within an upper end of the bore of the sleeve 14, which is slightly reduced

in diameter from the lower end thereof, thereby providing an annular shoulder 31, is a shell 32 which may be easily inserted and removed from the bore of the sleeve 14, 6 the fit between the shell and the inner periphery of the sleeve being loose but snug. Having an air tight fit within the bore of the shell 32 is a pneumatic cylinder 33 provided with an integral annular peripheral 10 collar 34 intermediate its ends, the upper annular surface of the collar abutting the shoulder 31, and also the lower end of the shell 32. Abutting the lower annular surface of the collar 34 is a comparatively short 15 shell 35 fitting tightly the periphery of the cylinder 33 to prevent the passage of air but loosely and snugly fitting the inner periphery of the sleeve 14. The collar 34 of the cylinder 33 and the tightly fitted shell 35 20 carried by the cylinder is firmly held against the shoulder 31 of the sleeve 14 to provide an air tight joint by a holding or retaining sleeve 38 which is threaded into the lower end of the sleeve 14. The retaining 25 sleeve 38 may be rotated by using a suitable tool inserted in diametrically opposite slots 39 formed in the lower annular surface of the sleeve 38. The upper end of the bore of the cylinder 33 has threaded thereinto a 30 plug or head 40, a shoulder 41 of which abuts the flush annular end surfaces of the cylinder 33 and the shell 32, thereby clamping the lower end of the shell against the upper annular surface of the collar 34 of the 35 cylinder and providing an air tight joint. Formed in the upper end of the cylinder 33 is a piston chamber 42 carrying a double acting balanced valve piston 45 provided with a hammer portion 46.

40 The peripheral surface of the cylinder 33 is provided with a pair of longitudinally extending air channels 47 (Figs. 2 and 3) connected at their upper ends by cross passages 48 which communicate with an air 45 inlet chamber 49 formed in the head 40. Intermediate their ends the channels 47 are disposed in communication with the piston chamber 42 by cross passages 53 and at their lower ends by cross passages 54 with a 50 turbine chamber 55 formed in the lower end of the cylinder 33, the purpose of which will be described presently. Also formed in the peripheral surface of the cylinder 33 is a pair of longitudinally extending air channels 56 (Figs. 1 and 2) connected at their upper ends with an air exhaust port 57 formed in the head 40 and at spaced points by cross passages 60 and 61 with the piston chamber 42. Spaced sets of air by-passing 55 channels 62 are also formed longitudinally in the peripheral surface of the cylinder 33, the channels being connected at opposite ends to the piston chamber 42 by cross passages 63. The various channels and cross 60 passages in the cylinder 33 are formed in

70 pairs to provide a certain air carrying capacity without deleteriously weakening the cylinder walls, although they might be arranged singly, dependent on the particular apparatus.

75 Mounted in the chamber 55 is an air actuated turbine unit comprising a stationary integral or one-piece outer shell or stator 64, fixed from longitudinal and rotary movement in the chamber by a set screw 67 (Fig. 3) threaded into the wall of the cylinder 33 with a reduced end thereof entered in a depression in the shell, and an inner integral or one-piece turbine rotor 68. Opposite ends of the rotor 68 extend outside the ends of the stator 64 and are each provided with an annular flared surface engaged by ball bearings 69 and 70, the bearing 69 being fitted in the upper end of the chamber 55 and the lower bearing 70 being supported upon the inner horizontal surface of an apertured cap 71 which is threaded into the lower end of the sleeve 14 below the retaining sleeve 38. After threading the cap 71 into the sleeve 14 to position the upper and lower bearings 69 and 70, respectively, against the flared surfaces of the rotor 68 with a desired rolling action, in which position cooperating surfaces to be presently referred to, upon the stator 64 and the rotor 68 are spaced from each other, a set screw 72 is threaded into the wall of the sleeve 14, a reduced end thereof being entered in a depression in the cap 71. Threaded axially into the cap 71 is an apertured 80 plug 74 having a reduced portion 75 extending through the bearing 70. The hammer portion 46 of the valve piston 45 projects through an axial aperture in the upper bearing 69, with its lower end normally positioned slightly within a circular upper end 85 of an axial aperture 77 provided in the rotor 68. The diameter of the hammer portion 46 is such that a suitable clearance is provided between the periphery thereof and the inner periphery of the circular end portion 76 of the aperture 77 of the rotor 68 so that no appreciable friction occurs between these parts.

85 The aperture 77, except for the circular upper end 76, is non-circular, as clearly shown in Fig. 5, and is provided with opposite flat wall portions. Reciprocably mounted in the aperture 77 is a riveting tool 78 having a work engaging head portion 81 at one end, an intermediate portion 82 which is circular in cross-section and reciprocable in the aperture of the plug 74 and a non-circular upper end portion 83 similar in cross-section to the non-circular portion of the aperture 77 of the turbine rotor 68, as clearly shown in Fig. 5. For a short distance from the extreme upper end of the tool 78 it is of slightly reduced diameter and circular in cross-section, as indicated 90

at 84 (Figs. 3 and 4), with a flat end surface thereof engageable with a similar face on the lower end of the hammer portion 46 of the piston 45. It will be apparent that 5 the non-circular portion 83 of the tool 78 reciprocably mounted in the non-circular aperture 77 of the rotor 68 provides a spline connection therebetween and permits a simultaneous reciprocation and rotation of 10 the tool by means of the piston 45 and the turbine rotor 68, respectively, the operation of which will be presently described.

The turbine stator shell 64 is formed with a plurality of blades 87 (Figs. 3, 4 and 5), the blades being integral with and arranged in sets at a plurality of equally spaced positions along the longitudinal axis of the shell with a continuous annular space between the adjacent sets of blades. The 15 blades 87 of each set, specifically nine in number, in the embodiment of the invention illustrated, are equally spaced around the inner peripheral surface of the shell 64. The blades 87 are each provided with faces 20 88 which are angularly disposed relative to the longitudinal axis of the shell 64. Integral with the outer peripheral surface of the rotor 68 and fitting into the annular spaces between the sets of blades 87 upon the shell 64 is a plurality of blades 89 arranged in sets, specifically twelve blades in each set. The blades 89 are equally spaced around the periphery of the rotor 68 and provided with faces 90 disposed at an angle 25 to the longitudinal axis of the rotor, the angle of the faces 90 differing in pitch, as well as direction, from the faces 88 of the blades 87. A slight clearance is provided at all points between the adjacent faces of the blades 87 and 89. Although in the particular embodiment of the invention herein illustrated and described the angle of the faces 88 and 90 of the blades 87 and 89, respectively, are different in pitch as well 30 as in direction, in some instances it may be found desirable to have the same pitch, although in different directions. The particular arrangement of the faces 88 and 90 will depend on the desired speed of rotation of the tool 78, but in all cases the faces should be in such angular relation, one to the other, that positive rotary motion will be imparted to the rotor 68 by the stator blades 87, which successively deflect the air against the 35 faces 90 of the blades 89 throughout the length of the rotor. The stator shell 64 may be formed before its assembly with the rotor 68 from a single member and then severed longitudinally into two equal halves, 40 which in the assembly of the turbine unit are assembled around the rotor and then welded or otherwise integrally united.

As hereinbefore described the air channels 47 connected at their upper ends to the air inlet chamber 49 are provided with cross

passages 54 at their lower ends (Fig. 3). The cross passages 54 lead to aligned passages 91 in the stator shell 64 which open into an annular chamber 94 formed in the rotor 68 above the uppermost set of blades 70 of the stator shell. An annular chamber 95 formed in the rotor 68 below the lowermost set of blades 89 thereof is connected to atmosphere by means of a plurality of passages 96 provided in the lower end of the stator shell 64 which open into an annular space 97 between the inner and outer peripheries of the cylinder 33 and the stator shell 64, respectively. The space 97 is connected to a plurality of slots 98 formed in the outer periphery of the bearing 70 and aligned with a similar number of passages 99 formed in the lower end wall of the cap 71.

The compressed air entering the annular chamber 94 in the rotor 68 passes downwardly between the angularly disposed faces 88 of the stator blades 87 in the direction indicated by the arrows (Fig. 4) and against the angularly disposed faces 90 of the rotor 68, which latter faces differ in direction and inclination from the faces 88 of the stator blades 87. After striking the rotor blade faces 90 the air is deflected downwardly and allowed to escape between the faces 88 of the next set of stator blades 87 and so on until it has traveled the entire length of the turbine rotor 68, passed into the chamber 95, and thence by way of the passages 96, space 97, slots 98 and passages 99, to atmosphere. As a result of the cumulative energy of the air blasts successively directed against the faces 90 of the plurality of sets of rotor blades 89 the rotor 68 will be continuously rotated upon the roller bearings 69 and 70 with great speed and force and through the spline connection between the riveting tool 68 and the aperture 77 in the rotor the tool will be similarly rotated simultaneously with its reciprocation by the valve piston 45, the operation of which will be presently referred to.

Mounted upon the top surface of the standard 10 is an air valve including a casing 102 which may be connected by a pipe 103 to a suitable source (not shown) for supplying air under pressure or any other suitable motive fluid. Reciprocably mounted in the valve casing 102 is a valve 104, the stem of which extends outside of the casing 102 with a rounded end 105 normally lying in the path of a cam face 106 provided on a collar 109 threaded onto a relatively short stop sleeve 110 which is threaded onto the reciprocable sleeve 14. The lower end surface of the stop sleeve 110 is predeterminedly spaced from the upper surface of the cylindrical collar portion 13 of the standard 10 so as to limit the downward movement of the sleeve 14 upon an actuation of

the link 26 in the manner hereinbefore described. The purpose of limiting the downward movement of the sleeve 14 will be made apparent shortly. By varying the position 5 of the collar 109 upon the stop sleeve 110 it will be apparent that the position in the downward movement of the sleeve where the cam face 106 engages the end 105 of the valve stem may be varied, thus varying the 10 amount of air permitted to pass through the valve casing 102. Retaining collars 111 are threaded onto the sleeves 14 and 110 and against the upper end surfaces of the sleeve 110 and the collar 109 for the purpose of 15 locking them in their predetermined adjusted positions. An air outlet chamber 112 of the valve casing 102 is connected to the air inlet chamber 49 of the head 40 on the cylinder 33 by a flexible hose 113. The 20 valve 104 is normally maintained against a seat in the valve casing 102 by the pressure of the air thereagainst, directed by the supply pipe 103, and is moved outwardly from the seat when the cam face 106 of the collar 109 engages the end 105 of the valve 25 stem, thus permitting the compressed air to pass through the valve casing and into the hose 113.

In operation, after an actuation of the 30 link 26 in the manner hereinbefore described, the sleeve 14 moves downwardly, carrying the work engaging head portion 81 of the riveting tool 78 into contact with the work, which is adjacently positioned on a suitable 35 fixture (not shown) supported under the tool. The downward movement of the sleeve 14 is sufficient to cause the tool 78 to be moved upwardly and through its engagement at its upper end with the hammer portion 46 of the valve piston 45, the latter is likewise raised to the dotted line position (Fig. 3). This movement of the valve piston 45 is determined by the distance the sleeve 14 travels before it is stopped by the 45 sleeve 110 engaging the cylindrical collar portion 13 of the standard 10. It is to be understood, however, that the distance the head 81 of the tool 78 has to travel to engage the work has to be taken into consideration 50 in adjusting the sleeve 110 upon the sleeve 14. In timed relation with the raising of the piston 45 the cam face 106 of the collar 109 engages the end 105 of the stem of the valve 104 and unseats the valve, permitting 55 the compressed air to pass through the valve casing 102 and to the air channels 47 of the cylinder 33.

In the dotted line position of the valve piston 45 the air inlet passages 53 are connected through the piston chamber 42 to the upper passages 63 of the lowermost by-passing channels 62 and by the latter to the lower passages 63 thereof to the lower end 60 of the piston.

65 The air entering the piston chamber 42 be-

low the valve piston moves the piston upwardly in preparation for a percussive movement downwardly and the spent air above the piston is exhausted through the passages 60, channels 56 and exhaust port 70 75 57 to atmosphere and upon the piston covering the upper passages 63 of the lowermost by-passing channels 62 and simultaneously clearing the lower passages 63 of the uppermost by-passing channels 62 the live air will be directed through the latter channels and the upper passages 63 thereof to the chamber 42 above the piston and the latter is driven downwardly, the hammer portion 46 striking the upper end of the riveting tool 78. 80 During the downward movement of the piston the spent air below the piston is exhausted through the passages 61, channels 56 and exhaust port 57 to atmosphere. After striking the tool 78 the piston 45 rebounds upwardly and the live air is again directed to the underside of the piston and another reciprocatory cycle of the piston, as before described, is completed, it being understood that a continuous percussive action of the 85 piston against the tool is effected as long as the treadle is held depressed with the head 81 of the riveting tool 78 in engagement with the work.

Simultaneously with the passage of the 90 air through the passages 53 into the piston chamber 42 the air is also directed along the channels 47 through the passages 54, 91 and into the chamber 94 of the turbine rotor 68, where, in the manner hereinbefore described, 100 it acts to continuously rotate the rotor 68 and the tool 78 splined thereto.

Referring particularly to Figs. 3, 6 and 7, it will be observed that the work engaging head portion 81 of the riveting tool 78 105 is formed with an arcuate or concave surface, which extends in one direction substantially across the width of the completed rivet head and in a direction at right angles thereto is relatively narrow so that it engages only a relatively small area of the end 110 of a rivet 115 before and after completion of the riveting operation. As a result of the simultaneous reciprocation and rotation of the tool 78, the rotary movement continuing during the percussive action of the concave head 81 of the tool against the end of the rivet, a spinning action is produced, the material of the rivet flowing outwardly, which action is greatly facilitated, due to 115 the percussive impacts being delivered at successively different concentrated small end areas of the rivet by the relatively small area of the concave surface of the tool head extending thereacross in one direction. This has a tendency to concentrate the force of the impacts at the upper end of the rivet, thus preventing the shank from bending or becoming deformed.

Although the invention as herein illus- 120 125 130

trated and described is particularly well adapted for use in connection with the upsetting of rivets, it should be understood that the novel features thereof are capable of other applications and should be limited only by the scope of the appended claims.

What is claimed is:

1. A motive fluid driven percussive apparatus, a standard provided with a hollow bearing portion, a reciprocating sleeve mounted therein, a motive fluid actuated tool unit carried by the sleeve, means journaled on the standard and operatively connected to the sleeve for causing reciprocation thereof, means for introducing motive fluid to the tool unit, including a valve carried on the standard, and means disposed on the sleeve and movable into and out of engagement with the valve at predetermined points in the reciprocation of the sleeve for controlling the operation of the tool unit.
2. In a motive fluid driven percussive apparatus, a supporting member provided with a hollow bearing portion, a reciprocating sleeve having a gear rack on its outer peripheral surface mounted in the hollow bearing portion, a motive fluid actuated tool unit carried within the sleeve, a gear journaled on the supporting member and arranged to mesh with the gear rack on the sleeve, manually operable means for rotating the gear for causing reciprocation of the sleeve, means for introducing motive fluid to the tool unit, including a control valve for the motive fluid mounted on the supporting member, and an annular member mounted on the sleeve and responsive to the movement of the sleeve at predetermined points in the reciprocation thereof for actuating the control valve for controlling the operation of the tool unit.

In witness whereof, I hereunto subscribe my name this 14th day of December, A. D. 1929.
